UNITED STATES PATENT OFFICE

FRANK J. ABEL, OF MASSAPEQUA, NEW YORK, ASSIGNOR TO HENRY HYMAN, OF BROOKLYN, NEW YORK

DESIGN FOR A CLOCK CASE

Application filed January 6, 1932. Serial No. 42,383. Term of patent 14 years.

To all whom it may concern:

Be it known that I, FRANK J. ABEL, a citizen of the United States, residing at Massapequa, county of Nassau, and State of New York, have invented a new, original, and ornamental Design for a Clock Case, of which the following is a specification, reference being had to the accompanying drawing, form-

ing a part thereof, in which Fig. 1 is a front elevational view of a clock case showing my new design, and Fig. 2 is a side elevational view of the same.

I claim:

The ornamental design for a clock case, as shown.

FRANK J. ABEL.
